UNITED STATES PATENT OFFICE.

JONATHAN W. CADWELL, OF NORTH READING, MASSACHUSETTS.

IMPROVEMENT IN REVOLVING STEREOSCOPES.

Specification forming part of Letters Patent No. **146,164**, dated January 6, 1874; application filed May 5, 1873.

To all whom it may concern:

Be it known that I, JONATHAN W. CADWELL, of North Reading, in the county of Middlesex and State of Massachusetts, have invented certain Improvements in Stereoscopes, of which the following is a specification:

Figure 1 of the accompanying drawing is a central vertical longitudinal section, and Fig. 2 is a central vertical transverse section, of my improved stereoscope-case. Fig. 3 is a part in detail of the same.

This invention relates to that class of stereoscopes in which the views are pivoted to a revolving horizontal shaft in such manner as, when revolved, to successively expose each picture as it reaches a vertical position over the shaft, those in front falling by gravitation, so as to expose the entire surface of the view, which is held by a suitable spring-detent. My invention has for its object to provide a stereoscope in which a greater number of views shall be held upon a single shaft than is usually done, and yet allow sufficient fall of the views, after passing a vertical line through the shaft, to expose the entire surface of the succeeding view. To this end it consists in the peculiar construction of the view holders or clamps, enabling them to lie closely together, and their arrangement on a peculiarly-constructed shaft or roller, as I will now proceed to describe.

In the drawings, *a* represents a stereoscope-case, formed with suitable eye-pieces *b b'*, arranged as usual, and provided on the top with hinged lids *c*, lined with tin-foil or other reflecting substance. Within the case *a*, extending transversely, is a roller or axle, *d*, whose ends *d'* are supported by and turn in the sides of the case *a*. At each end of the roller *d* are attached two parallel plates or disks, *e e'*, formed with a series of perforations, *f*, near the edge of the circumference, in which the ends of transverse rods *g'* are held and allowed to turn. Between the parallel disks *e e'* and *e' e'* are side flaps or clamps *h h'*, that are bent at the bottom, so as to turn on and be held by the rods *g'*, and form two outward-extending portions or arms. The back portion or arm of the flaps is curved at the upper portion and rounded at the edge, as shown, to prevent the interference of one series of flaps with the other in their rotation, and to receive the ends of sta-

tionary rods *g*, that connect the flaps on one side with the flaps on the opposite side, and extends horizontally across the top, and is rounded on the front edge, and formed with a downward-extending lip or catch, *h''*, that turns over and holds the top of the front portion or arm of the flaps. On the top of the flaps being raised, the catch is unloosed and the front arms released for the admission of the views, whose sides are held between the front and back portions or arms of the flaps, from which the views are readily withdrawn by raising the tops of the flaps and releasing the lips or catches *h''* from the front arms. The bottoms of the flaps *h h'* are formed at front and back with double-reversed curves, as shown in Fig. 3, so that the convex portion of one flap will impinge against the concave portion of the other flap when together, and thus allow a greater number of flaps to be connected with the plates *e e'*, and permit of their rotation without the interference of one with the other. The roller *d* is provided with and operated by a suitable crank or knob, *k*, arranged on one or both sides of the case *a*. Within the case *a*, on each side, at the top, is a bent rod or spring, *l*, held by a screw or stem, *l'*. This rod or spring is only necessary for the use of transparent views, and is so bent or arranged as to allow the passage of the rods *i* and views in one direction, and prevent their falling backward, so that when the desired view is brought properly in sight by the rotation of the axle *d* it will be prevented, by the spring or rod *l*, from falling back.

The rods *g* may, if desired, be attached to the top of the flaps *h h'* on the outside.

By my improvements, as shown in the accompanying drawings, and as hereinabove described, it will readily be seen that a great number of flaps for the reception of the views may be arranged within the case, requiring but a small space for their operation, thus enabling a smaller box than ordinary to be used; and as the several operative parts are simple and inexpensive in construction and cost, the apparatus can be furnished at less expense than the larger and ordinarily-constructed stereoscopes of similar description. Moreover, by the arrangement and operation of the flaps *h h'*, as hereinabove described and shown, it will be

seen that they are readily operated without the interference of one series with the other; and that the views are readily adjusted and securely held in or easily withdrawn from the flaps; and that the objections occasioned hitherto by the interfering and falling out of the views is obviated.

Having thus fully described my improvements, what I claim as my invention, and desire to have secured to me by Letters Patent, is—

1. In a stereoscope for revolving views, the clamps h h' pivoted to longitudinal rods g' on a revolving axle, said clamps being adapted to fit snugly together at their inner ends by means of reverse curves or corrugations, sub-

stantially as described, for the purpose specified.

2. The axle d having the parallel plates e e' , the latter containing the rods g' , in combination with the clamps h h' , pivoted at their inner ends to the rods g' , and connected at their outer ends by the rods i , substantially as described.

In testimony whereof I have signed my name to this specification in the presence of two subscribing witnesses.

JONATHAN W. CADWELL.
